FOREIGN PATENT DOCUMENTS

GB 2031463 * 11/1993

Primary Examiner—Carol Rademaker

(74) Attorney, Agent, or Firm—Dinsmore & Shohl LLP

(57) **CLAIM**

The ornamental design for a bottle, as shown and described.

DESCRIPTION

FIG. 1 is a front elevation.

FIG. 2 is a rear elevation.

FIG. 3 is a left side elevation.

FIG. 4 is a right side elevation.

FIG. 5 is a perspective view of the front and right side.

FIG. 6 is a perspective view of the front and left side.

FIG. 7 is a perspective view of the rear and right side.

FIG. 8 is a perspective view of the rear and left side; and,
FIG. 9 is a top plan view.The broken lines of a bottle cap shown in all drawing views
are included for the purpose of showing environmental structure
that forms no part of the claimed design.**1 Claim, 5 Drawing Sheets**# US D581,276 S
